UNITED STATES PATENT OFFICE.

JOHN L. HAMILTON, OF ST. JOSEPH, MISSOURI.

IMPROVEMENT IN RAILWAY-CAR SEATS AND COUCHES.

Specification forming part of Letters Patent No. 130,219, dated August 6, 1872.

Specification describing a new and Improved Berth and Seat Arrangement for Sleeping-Cars, invented by JOHN L. HAMILTON, of St. Joseph, in the county of Buchanan and State of Missouri.

Figure 1 represents a plan view of my invention. Fig. 2 is a vertical transverse section of one of the seats and berths, the line *c c*, Fig. 1, indicating the plane of section. Fig. 3 is a front elevation of the same.

Similar letters of reference indicate corresponding parts.

The invention consists in a new mode of combining the seat-back with sliding frames, and in the use of auxiliary backs, as hereinafter fully described.

A in the drawing represents part of the car-body, within which a suitable number of seats, *B B*, are set up at proper distances apart. Each seat is, by one leg, *a*, next to the side of the car, pivoted to the car bottom *b*, the leg having a pendent pivot-pin, *d*, which enters a socket in the car bottom, as shown. The seat can on this pivot be turned at an angle of about forty-five degrees to the side of the car, in which case, by the interposition of a triangular plate, *e*, between the end of the seat and the car, an extension is effected fitting it to a berth. This extension-plate *e* rests on a rib, *f*, that projects from the side of the car, and by projecting dowels *g*, also, on the end of the seat. By being thus swung into the oblique position, as is shown in the upper part of Fig. 1, the seats are brought close together and utilize, consequently, to the fullest extent, the space in the car, the extension *e* being sufficient to convert each seat into a comfortable couch. The back *h* of each seat is pivoted at the ends in the ordinary manner, to be reversible, and can be sustained horizontally above the seat on frames *i i* that slide

in the ends of the seat, as indicated in Fig. 2. The frames *i*, when elevated to sustain the back, are locked by suitable catches *j*. The back constitutes in this position another couch above the seat, and receiving an extension, *e*, similar to the other, will be equally long and comfortable. Side guards *l l* may be arranged removably on the backs *h*, to be used only when the same are in position as upper couches. *m m* are auxiliary backs hinged to the under side of each seat, to be used when the back proper *h*, is turned up. These backs *m* may also serve as guards for the lower couches, as in Fig. 2.

In order to utilize as fully as possible the space within the car, that upright of the seat-frame *n* which would be nearest the side of the car when the seat is swung into the oblique position may be left off by giving additional strength to the other upright. Proper head-rests *o* may be removably applied to the ends of the upper and lower couches. The outer part of the seat may be supported on a circular metallic track, *p*, sunk into the floor of the car, and arranged with sockets or catches, or both, to lock the seat in its several positions.

Having thus described my invention, I claim as new and desire to secure by Letters Patent—

1. The back *h* of a railroad car-seat, when arranged in combination with the sliding frames *i*, whereby it is held above the seat as an upper couch, as specified.
2. The auxiliary backs *m m* applied to a car-seat, substantially as and for the purpose herein shown and described.

JOHN LINTON HAMILTON.
